UNITED STATES PATENT OFFICE

JOHN HERBERT PIPER, OF MOTTINGHAM, ENGLAND

SELF-ACTING MECHANISM FOR OPERATING SLIDING WINDOWS

Application filed April 27, 1928, Serial No. 273,369, and in Great Britain June 24, 1927.

This invention relates to automatic or self-acting mechanism for operating sliding windows and the like and has for its chief object to provide simple, reliable and efficient mechanism for that purpose.

The invention is chiefly, but not exclusively, applicable to the sliding windows or side screens of motor vehicles.

According to the present invention, there is operatively coupled or connected to the sliding window sash or the like, an extensible and collapsible support furnished with or controlled by one or more springs constantly tending to expand or extend the support to close or elevate the window sash or the like or hold it in the closed position, and a one-way acting hand-controlled clutch which maintains the window sash in any position of adjustment or extent of opening against the action of the controlling spring or springs.

The power of the springs is so regulated in accordance with the weight and frictional resistance of the window sash or the like that the closing or elevating movements will be gentle or gradual and free from violence or shock.

Referring to the accompanying drawings:

Fig. 1 is a front elevation showing a device constructed in accordance with or embodying the present invention.

Fig. 2 is a front elevation, partly in section, showing the device as illustrated in Fig. 1 applied to a window sash structure, the window sash being shown in the closed position.

Fig. 3 is a view similar to Fig. 2 but with the window in an open position.

Fig. 4 is a diagrammatic view showing a modified construction of control mechanism.

Figs. 5 and 6 are diagrammatic views showing further modified constructions of the control mechanism.

Referring to the arrangement shown in Figs. 1 to 3, the collapsible support comprises a lower pair of levers or bars A A¹ and an upper pair of similar levers or bars A² A³.

As shown in Figs. 2 and 3 the device is

applied to a sliding window sash Y of a window structure Z such as employed in closed motor vehicles, railway cars or the like, and the support A A¹ A² A³ is arranged in the chamber or space X into which the sash descends when opened (see Figs. 2 and 3).

The lower or meeting ends of the levers A A¹ are pivotally connected at a to a stationary or fixed block or bracket A⁴ at the lower end of the chamber X.

The upper ends of the bars or levers A A¹ are pivotally connected at a¹ to the lower ends of the levers A² A³ respectively, and the upper ends of these latter levers are pivotally connected to a block A⁵ which is attached to the lower end of the sash Y, or the upper ends of the levers A² A³ may be pivotally connected to the frame of said sash.

Around each of the pivots a¹ connecting the upper and lower pairs of bars or levers are arranged coil springs B, one end b of each spring being adapted to bear on a pin or stud A⁶ on one of the upper levers while the other end b¹ bears upon a similar pin or stud A⁷ on one of the lower bars or levers. Or two springs B B¹ may be arranged around each of the pivots a¹.

These springs constantly tend to extend or open the support A A¹ A² A³ to move the window sash to the closed position (Fig. 2).

A convenient construction of a one-way controlling clutch for the device comprises two opposed eccentrics C C¹ which are mounted loosely on axes c, c¹ respectively, carried conveniently by the block or bracket A⁵.

These eccentrics are normally pressed towards each other conveniently by springs C⁴ to grip between them a band or tape C² of canvas or other material which in the present example is stationary, the upper end being attached to a stationary part of the window structure and the lower end to a fixed bar at the lower end of the chamber X, so that this tape is constantly maintained taut or in tension.

When the sash Y is pushed down, say by hand pressure, pressure being applied conveniently through a knob or handle Y¹ the friction between the tape and the eccentrics

causes the latter to turn on their pivots in a direction away from the tape and thus allow the sash to descend freely.

The power of the controlling springs B, B¹ is contrived so that they are just sufficient to raise the sash, when the clutch is released, and said power is applied between the pairs of levers so that as the springs are wound up the leverage increases and vice versa.

- 10 When pressure is removed from the sash, the eccentrics immediately grip the tape again and hold the sash in any adjusted position. The power of the springs is thus regulated in accordance with the weight and 15 frictional resistance of the sash so that the closing or elevating movements will be gentle or gradual and free from violence or shock.

When it is desired to close or elevate the 20 sash the clutch formed by the eccentrics must be temporarily released. This may be accomplished in various ways; in the example illustrated the eccentrics are controlled by a "Bowden" cable D of known construction. 25 One end d of the movable member of the cable is attached to the eccentric C¹ and the other end d¹ to an operating handle or lever D¹.

The clutch formed by the eccentrics C C¹ 30 is shown attached to the moving window sash, and the "Bowden" cable permits the sash to move freely without interfering with the control.

In some positions, where the use of a 35 "Bowden" cable may not be convenient, a converse arrangement of control to that already described may be employed. In such a case the clutch or eccentrics C C¹ may be mounted on a stationary support and the 40 tape C² be made to travel. In this case the tape will be endless and mounted to run over two pulleys C¹⁰ C¹¹ arranged one at the top of the sash receiving chamber and the other at the lower end thereof, and the tape can 45 be secured to the sliding sash by a stud or other suitable fastening. For operating one of the eccentrics with this arrangement a lever may be connected say to the eccentric C¹ to cause it to rotate or turn on its pivot.

50 Referring now to the modified construction of clutch shown in Fig. 5 this comprises the wedges C⁵ C⁶ which are arranged on opposite sides of the tape C² to move longitudinally in guides and between two stationary 55 stops C⁷ C⁸. These wedges are constantly pressed downward to grip the tape by springs C⁹.

58 A lever C¹² is pivoted to the support for the wedges, and one arm of this lever passes under studs C¹⁰ on the wedges and is controlled by a spring C¹¹. Said lever may be operated by hand directly or through suitable devices to move the wedges and release the sash.

63 As shown in Fig. 6 one of the wedges may be replaced by a friction roller C¹⁴.

In the above described arrangements the sashes are opened by pressure applied by hand directly to the sash itself but the control for the clutches may be arranged both to close and open the window. Such an arrangement is shown in Fig. 4. In this arrangement the clutch comprising two eccentrics C C¹ as in Fig. 1 is mounted on or is movable with the sliding sash.

The tape C² is endless and is carried around two stationary idle pulleys or rollers C¹⁰ C¹¹ and round a winding or controlling pulley C¹⁵ which may be operated by a handle C¹⁶.

70 When the pulley C¹⁵ is rotated clockwise the movement of the tape will cause the eccentrics to grip it and cause the sash to be lowered, and when the pulley C¹⁵ is rotated counterclockwise the movement of the tape will turn the eccentrics to release their grip and the sash will be elevated by the springs B B¹ acting on the support A A¹ A² A³.

75 Having thus described the invention what I claim is:

1. In a window structure, the combination of a sliding sash; a system of levers pivotally connected together to form a four-sided support for the sash; springs acting on all the levers to close said sash; a self-acting clutch; a stationary member other than the sash with which said clutch coacts to retain the sash 95 in any position of adjustment against the action of said springs; and a device operable at will on the clutch to open the same temporarily.

2. In a window structure, the combination 100 of a sliding sash; a pair of downwardly-diverging levers having their upper ends pivotally connected to the lower end of the sash; a pair of upwardly-diverging levers disposed below the first pair and pivotally connected 105 at their upper ends to the lower ends of said first pair and at their lower ends to a fixed member; springs at the mutually-connected ends of the two pairs of levers and acting on both pairs to close the sash; a self-acting 110 clutch; and a stationary member other than the sash with which said clutch coacts to retain said sash in adjusted position against the action of the springs.

3. In a window structure, the combination 115 of a sliding sash; a pair of downwardly-diverging levers having their upper ends pivotally connected to the lower end of the sash; a pair of upwardly-diverging levers disposed below the first pair and pivotally connected 120 at their upper ends to the lower ends of said first pair and at their lower ends to a fixed member; springs at the mutually-connected ends of the two pairs of levers and acting on both pairs to close the sash; a self-acting 125 clutch; a stationary member other than the sash with which said clutch coacts to retain the sash in any position of adjustment against the action of said springs; and a de- 130

vice operable at will on the clutch to open the same temporarily.

4. In a window structure, the combination, with a frame, and a sash sliding therein; of a pair of downwardly-diverging levers having their upper ends pivotally connected to the lower end of the sash; a pair of upwardly-diverging levers disposed below the first pair and pivotally connected at their upper ends to the lower ends of said first pair and at their lower ends to a fixed member; springs at the mutually-connected ends of the two pairs of levers and acting on both pairs to close the sash; a self-acting clutch at one end of one pair of levers; a tensioned band connected with the frame and whereon said clutch acts; and hand-controlled means operable at will on the clutch to open the same temporarily.
- 20 5. A window structure according to claim 4, in which the upper ends of the upper pair of levers are pivoted directly together as well as to the sash, and the lower ends of the lower pair of levers are pivoted directly together as well as to the fixed member; and in which the clutch is arranged at the connected upper ends of the upper levers and acts on the upper portion of the tensioned band.

6. In a window structure, the combination of a sliding sash; a pair of downwardly-diverging levers having their upper ends pivotally connected to the lower end of the sash; a pair of upwardly-diverging levers disposed below the first pair and pivotally connected at their upper ends to the lower ends of said first pair and at their lower ends to a fixed member; springs at the mutually-connected ends of the two pairs of levers and acting on both pairs to close the sash; a one-way clutch embodying two operatively-associated eccentric discs; and a member other than said sash with which both discs coact to hold the sash in adjusted position against the action of the springs.

45 7. In a window structure, the combination of a sliding sash; a pair of downwardly-diverging levers having their upper ends pivotally connected to the lower end of the sash; a pair of upwardly-diverging levers disposed below the first pair and pivotally connected at their upper ends to the lower ends of said first pair and at their lower ends to a fixed member; springs at the mutually-connected ends of the two pairs of levers and acting on both pairs to close the sash; a one-way clutch embodying two operatively-associated eccentric discs; a member other than said sash with which both discs coact to hold the sash in adjusted position against the action of the springs; and hand-controlled means operable at will on said discs to release them temporarily.

8. In a window structure, the combination, with a frame, and a sash sliding therein; of a pair of downwardly-diverging levers having

their upper ends pivotally connected to the lower end of the sash; a pair of upwardly-diverging levers disposed below the first pair and pivotally connected at their upper ends to the lower ends of said first pair and at their lower ends to a fixed member; springs at the mutually-connected ends of the two pairs of levers and acting on both pairs to close the sash; a clutch embodying two coacting gripping parts; a band fixed at opposite ends to stationary parts of the frame and passing between the gripping parts to be engaged by them, whereby the sash is held in adjusted position against the action of the springs; and a hand-controlled device operable at will on said gripping parts to release them temporarily.

9. In a window structure, the combination, with a frame, and a sash sliding therein; of a pair of downwardly-diverging levers having their upper ends pivotally connected to the lower end of the sash; a pair of upwardly-diverging levers disposed below the first pair and pivotally connected at their upper ends to the lower ends of said first pair and at their lower ends to a fixed member; springs at the mutually-connected ends of the two pairs of levers and acting on both pairs to close the sash; a self-acting clutch at one end of one pair of levers; and a tensioned band connected at opposite ends to stationary parts of the frame and whereon said clutch acts.

10. In a window structure, the combination, with a frame, and a sash sliding therein; of a system of levers pivotally connected together to form a four-sided support for the sash; springs acting on said lever system to close said sash; a stationary vertical member connected at top and bottom with said frame; and a self-acting clutch carried by the sash and operative on said member to retain the sash in any position of adjustment against the action of said springs.

11. A sash-retaining structure according to claim 10, in which the member whereon the clutch acts consists of a tensioned band.

12. A sash-retaining structure according to claim 10, in which the self-acting clutch comprises a pair of spring-actuated gripping parts disposed at opposite sides of the stationary vertical member for operation thereon.

13. A sash-retaining structure according to claim 10, in which the member whereon the clutch acts consists of a tensioned band; and in which the clutch itself comprises a pair of operatively-associated gripping parts disposed at opposite sides of said band for operation thereon.

In testimony whereof I affix my signature. 125
JOHN HERBERT PIPER.
